UNITED STATES PATENT OFFICE.

JOHANN G. PETERSON, OF JERSEY CITY, NEW JERSEY.

ELECTRICAL ATTACHMENT-PLUG.

1,288,980.

Specification of Letters Patent. Patented Dec. 24, 1918.

Application filed November 23, 1917. Serial No. 203,619.

To all whom it may concern:

Be it known that I, JOHANN G. PETERSON, a citizen of the United States, residing at Jersey City, in the county of Hudson and State of New Jersey, have invented certain new and useful Improvements in Electrical Attachment-Plugs, of which the following is a specification.

This invention relates to electrical attachment plugs, the object of the invention being to provide an appliance of this kind which can be easily connected to an incandescent lamp socket or its equivalent, for instance a socket of the Edison type, and which has at the same time means for the association of an extension connection therewith, the construction being simple, effective, compact and inexpensive to produce.

In the drawings accompanying and forming part of the present specification I show in detail one convenient form of embodiment of the invention, which to enable those skilled in the art to practise the same will be set forth in detail in the following description. I do not necessarily restrict myself to this exact disclosure; I may depart therefrom in several respects within the scope of the invention defined by the claim following said description.

Referring to said drawings:

Figure 1 is a bottom plan view of an electrical attachment plug involving the invention.

Fig. 2 is a longitudinal central vertical section of the plug.

Fig. 3 is a bottom plan view of the same.

Fig. 4 is a transverse section on the line 4-4 of Fig. 2, looking in the direction of the arrows.

Figs. 5 and 6 are detail views in perspective of connectors.

Like characters refer to like parts throughout the several views which are on different scales.

The appurtenance comprises in its make-up a suitable body which is generally of circular form in cross section. In fact the body may be in the main cylindrical and may taper toward one end. A body such as that denoted in a general way by 2 answers my requirements in a satisfactory manner. This body may be made of porcelain or some composition of insulating material. Its reduced end has fitted around it the contact shell 3 usually made from sheet brass and preferably threaded to fit an Edi-

son socket. The reduced end of the insulating body 2 has a projection or key 4 extending centrally therefrom and through the slot 5 in the flange 6 of the contact shell 3, 60 this flange overlying and fitting flatwise against the reduced end of the body or core 2.

The larger end of said body or core has a socket 7 to receive the contact shell 8, 65 said contact shell 8 having upon its bottom the inwardly extending flanges 9 and 10 which fit against the bottom of said socket. This shell 8 constituting a suitable contact, is preferably internally threaded to receive 70 the plug or shell portion of a lamp or the like. The shell 3, as will be understood, is adapted to fit within a co-operating shell of a socket. The flanges 9 and 10 of the contact shell 8 are perforated to receive the 75 screws 11 and 12, the shanks of which project through openings 13 and 14 extending from the socket 7 to the reduced end of the insulating body or core 2. The threaded portions of these screws fit threaded openings in a washer as 15 fitted against the flange 6 of the exterior shell 3, the heads of the screws acting against the flanges 9 and 10 respectively of the interior shell 8 to hold 80 the parts assembled.

In addition to the two lateral openings or holes 13 and 14, the body or core 2 has a central hole 17 extending from the chamber 7 to and through the projection or key 4. Projecting entirely through the hole or opening 17 is the screw 18 to which is connected the disk or nut 19 constituting a central end contact, the head of the screw 18 constituting a companion end contact, although the head 18 has means as I will hereinafter explain which co-operates therewith to present the central end contact at the place in question.

It will be supposed that the plug end of the article or that equipped with the shell 3, is fitted into an incandescent socket in such manner as to bring the shell 3 into electrical connection with the shell of the socket and the contact 19 into electrical connection with the central end contact of the socket. In this case the appliance will be in the "on" relation, so that for instance if a lamp be screwed into the shell 8 until its central end contact engages the head portion of the screw 18, the lamp will light. Any other 110 suitable appliance can, of course, be inserted in the shell 8. The screws 11 and 12 in the

illustration given will, of course, function in the conduct of current, although the screw 11 is primarily intended for this purpose. Nevertheless the screw 12 does act in the particular capacity mentioned, although the screw 12 or equivalent means is primarily provided to hold the parts in assembled relation.

Extending centrally from the bottom of 10 the socket 7 and in one piece with the body 2, is the projection 20 which is approximately rectangular in form and against which the head of the central screw 18 already described bears, although in the present case not directly. Coöoperative with the central screw 18 and the lateral or side screw 11 are connectors such as those denoted in a general way by 21 and 22 and shown in detail respectively by Figs. 6 and 5. The 15 body of the connector 21 is denoted by 23 and is in the form practically of a disk having a central perforation to receive the screw 18 which is countersunk in the perforation, so that the head of the screw and the disk portion 23 are practically flush for engagement as already noted, by the central end contact of the plug portion of a lamp introduced into the shell 8. This body 23 is provided with the laterally extending portion 23 which is bent downward as at 25 and then forward as at 26, beyond which it is continued as at 27 to form a resilient or 20 spring contact, the body 2 having the channel 28 to receive practically the entire projecting portion of the connector 21.

The body 2 externally thereof and practically centrally of its length, is furnished with the boss or hub 29 having through it the opening 30 in register with the channel 40 or groove 28 and receiving the contact finger 27. This contact 27 is adapted to directly 45 coat with a complementary contact as will hereinafter appear.

The flange 9 of the shell 8 has upon it the 45 body 31 of the connector 22, said body fitting around the projection 20 which I have already described, and being perforated to receive the screw 11, the head of the screw holding the body 31 against and in electrical 50 engagement with the flange 9. This body

31 is provided with the downwardly-extending portion 32 having the outwardly-extending portion 33 presenting a contact complementary to and in parallelism with the contact 27. The body 2 has a channel 34 to receive the projecting portion 32 and contact 33, which contact extends into the hole 35 in coincidence with the channel or groove 34.

The cap portion 36 is provided with the contacts 37 and 38 to which the wires 39 are connected, the butt portions of the two contacts extending from the cap 36 so as to be introduced into the openings 30 and 35 to engage the spring contacts 27 and 33. When it is desired to disconnect electrically the cap 36 from the plug proper, it will be pulled to the right in Fig. 2. When the cap is in place, however, the inner flat face of its insulating body fits practically flatwise against the outer face of the hub or 70 boss 29.

What I claim is:

An electrical attachment plug comprising an insulating body, a contact shell fitted over one end of the body, the other end of the body having a socket, a contact shell fitted in said socket, a screw disposed centrally of the body and extending from the bottom of said socket to the other end of the body, the ends of said screw having central end contacts, two other screws at opposite sides of said central screw, extending from one shell to the other, a one-piece electrical connector through the body of which said central screw extends, the insulating body 85 having a side opening into which said connector extends, and a second one piece electrical connector through the body of which one of the screws at opposite sides of said central screw, extends, the insulating body 90 having a second side opening into which the second connector extends, the two extended portions of said connectors constituting terminals for a tap connection.

In testimony whereof I affix my signature 95 in the presence of two witnesses.

JOHANN G. PETERSON.
